Primary Examiner — Joseph Kukella*Assistant Examiner* — Heather Wencl(74) *Attorney, Agent, or Firm* — Murray, Ziel & Johnston; Aaron Powell(57) **CLAIM**

The ornamental design for a trash can lid lock, as shown and described.

DESCRIPTION

FIG. 1 is a rear and right side perspective view of a trash can lid lock, showing my new design;

FIG. 2 is a front and right side perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is an enlarged view of portion 9 in FIG. 2;

FIG. 10 is an enlarged view of portion 10 in FIG. 7; and,

FIG. 11 is an enlarged view of portion 11 in FIG. 8.

The evenly dotted broken lines depict stitching of the trash can lid lock and form no part of the claimed design. The unevenly dashed broken lines define the boundaries of enlarged views and form no part of the claimed design.

1 Claim, 11 Drawing Sheets(56)
